UNITED STATES PATENT OFFICE.

JOHN D. MACCARTHY AND HENRY O. MOULTON, OF ISHPEMING, MICHIGAN.

METHOD AND APPARATUS FOR CONDUCTING MINING OPERATIONS.

Application filed July 2, 1921. Serial No. 482,162.

To all whom it may concern:

Be it known that we, JOHN D. MACCARTHY and HENRY O. MOULTON, both citizens of the United States, residing at Ishpeming, 5 in the county of Marquette and State of Michigan, have invented certain new and useful Improvements in Methods and Apparatus for Conducting Mining Operations, of which the following is a specification.

10 This invention relates to mining systems and apparatus therefor and has for its primary objects to reduce the amount of underground labor and increase the mine output by providing an apparatus of small dimensions and simple operation which can be easily moved about the mine and which will rapidly, economically and efficiently handle the ore.

Further objects of the invention are to 20 eliminate hand shovelling by automatically loading the ore at the breast and transporting it without rehandling to the dumping point; to eliminate both the construction of tracks with ties and the hand pushing 25 of mining cars; to facilitate the transportation of the ore from the breast to the dumping point and thus make possible the use of a small power unit; to thoroughly clean up the breast; to eliminate manual labor in 30 transporting timber to the working face; to provide a simple and inexpensive overhead trolley system for trammimg the ore; to facilitate the extension of the apparatus as the mining operations progress; to provide 35 an advantageous form of trolley or carrier construction; to provide a power unit transportable on the same overhead system as the shovel skip; to provide a novel and advantageous means for switching the power 40 unit and shovel-skip to the various parts of the mine; to permit the handling of the ore in narrow or badly crushed drifts where the usual tram cars can not be used; to prevent the scattering of ore in the drift during 45 trammimg; to eliminate noise and confusion; to provide a system which can be readily set up and taken down; to permit the use of electrical power wherever practicable or desirable; to eliminate the necessity 50 for specially constructed stands or inclines for loading the cars and the shifting of cars on the main level during loading;

to permit the loading of cars of any dimensions; to provide an apparatus which loads by a forward and upward movement rather than by dragging; to permit the trammimg of the ore direct from the breast to the raise regardless of the bends or turns of the drift; and in general to provide a new and improved mining system and apparatus. 55 60

The many other objects and advantages of the present invention will be better understood by reference to the following specification when considered in connection with the accompanying drawings illustrating a selected embodiment thereof, in which:— 65

Fig. 1 is a partially diagrammatical side elevation of a sub-level drift equipped with our improved mining apparatus.

Fig. 2 is the same as Fig. 1, plan view. 70

Fig. 3 is a diagrammatical view showing the shovel-skip in the loading position.

Fig. 4 is a diagrammatical view showing the shovel-skip hoisted to trammimg position upon completion of the loading. 75

Fig. 5 is a diagrammatical view showing the shovel-skip dumping at the dumping point.

Fig. 6 is a diagrammatical view showing the empty shovel-skip returning to the loading point after the dumping operation. 80

Fig. 7 is a plan view of the power unit.

Fig. 8 is the same as Fig. 7, side elevation.

Fig. 9 is a vertical section on the line 9—9 of Fig. 7. 85

Fig. 10 is a detail plan view of the turntable.

Fig. 11 is a detail side elevation of the turntable shown in Fig. 10.

Figs. 12 and 13 are respectively detail plan view and side elevation of the shovel-skip detached. 90

Fig. 14 is a detail view of a type of tongs suitable for handling mine timber.

Fig. 15 is a side elevation of the carrier. 95

Fig. 16 is a front elevation, partially in section, of the carrier shown in Fig. 15.

Figs. 17 and 18 are detail views illustrating the method of suspending the trackage from the roof beams of the mine. 100

Fig. 19 is an end elevation of the power unit supporting frame showing jacks connected thereto to prevent rocking of the unit during the operation of the apparatus.

Fig. 20 is a top plan view of the automatic dumping device.

Fig. 21 is the same as Fig. 20, end elevation.

Fig. 22 is the same as Fig. 20, partial side elevation.

Fig. 23 is a detail side elevation of one of the jacks on the power unit.

Fig. 24 is a section on the line 24—24 of Fig. 9.

Figs. 25 and 26 are detail views illustrating the method of securing together adjacent units in a multi-unit system.

Fig. 27 is a diagrammatical plan view illustrating the use of the invention in a typical iron ore sub-level.

Fig. 28 is a diagrammatical elevation of a portion of a mine showing the power unit located upon a truck or car at the bottom 20 of the raise and the cables carried to the sub-level by idlers.

Fig. 29 is a diagrammatical view showing the breast cleaning up and the shovel-skip replaced by timber tongs to enable the timber to be hoisted in the raise and transported to the breast.

Fig. 30 is a diagrammatical elevation showing the adaptation of the apparatus to a main level drift.

Fig. 31 is a diagrammatical plan view illustrating the use of the apparatus in a small drift driven through rock.

Referring to the drawings, and particularly to Figs. 1 to 6 inclusive, the sub-level drift 20 is provided with the usual timber columns 21 and the roof supporting beams 22. A pile of loose material 23 has been excavated at the breast 24 of the drift and is ready to be carried to the usual raise 25.

One or more monorail tracks 26 preferably consisting of I-beams are suspended by chains 27 from the roof supporting beams 22 and extend longitudinally of the drift. The number of tracks in a drift is dependent upon the width of the drift but in view of the fact that these tracks and the mechanisms operating thereon are the same, only one will be described in detail as this description will be equally applicable to the others.

The chains 27 have their opposite extremities connected to rings 170 which pass through perforations in the opposite ends of the track support 171. The length of the track sections is preferably such that the joints between sections occur below the roof supporting beams of the mine, as indicated in Fig. 17. The track support 171 spans the joint and is preferably secured to the track sections by bolts 172 passing through the web of the track.

A trolley or carrier 28 travels on the track 26 and a power unit 29 is supported by this track and travels thereon independently of the carrier 28. A loading and traversing cable 30 connects the carrier 28 with the

operating drum 31 in the power unit 29. A hoisting and traversing cable 32 connects the hoisting drum 33 with the carrier 28. The cable 30 is supported by idler sheaves 34 mounted on the track 26. The outer end of this cable is divided at 35 and the branch 36 passes about the sheave 37 and has its ends secured to the cable adjusting drum 38 on the carrier 28. The other branch 39 of the cable 30 passes over the sheaves 40 and 41 and has its outer end connected to the forward position of a shovel-skip 42. The sheave 41 is mounted upon a cross-beam 43 at the breast. The hoisting and traversing cable 32 passes over the sheave 44 on the carrier 28 and thence downwardly around the lower sheave 45 connected to the shovel-skip 42 and has its outer end 46 secured to the carrier 28.

In Figs. 1 and 2 of the drawings two 85 overhead tracks are shown, each equipped with its own power unit, carrier, shovel-skip and operating cables. One of the shovel-skips 42 is shown in the loading position near the breast 24 and the other is just completing the dumping operation at the raise 25. A turntable 47 is provided at track intersections to enable the carrier and shovel skip to be transferred from one portion of the mine to another. The construction and mode of operation of this turntable will be more fully described herein-after. The drums 31 and 33 may be operated by any convenient kind of power, but we prefer to use an electric motor 48 100 wherever practicable. A dumping device 49 is preferably provided at the dumping point to automatically empty the shovel-skip 42. This dumping device may be attached to the track at any point though it is usually located above the raise in sub-levels. An advantageous form of dumping mechanism is shown in detail in Figs. 20 to 22 inclusive. This device is omitted from the general figures of the drawings to avoid confusion. A trip 51 is preferably provided above the loading point to automatically release the shovel-skip and cause it to be lowered into the loading position.

Referring to Figs. 3 to 6 inclusive, the shovel-skip in Fig. 3 is shown in the loading position at the start of the loading operation. The shovel-skip is here being drawn toward the pile of loosened material 23 by the cable 30 and simultaneously slowly hoisted by the cable 32, the drums 31 and 33 being engaged. The divided ends 36 and 39 of the cable 30 cause the carrier 28 and the shovel-skip 42 to move forwardly in substantially vertical alignment. The forward and upward movement of the shovel-skip during the loading operation under the action of both drums is very advantageous because it prevents stalling of the shovel-skip in very rough dirt or upon encounter-

ing a large chunk buried in the pile. As soon as the shovel-skip is filled and drawn clear of the pile of loose material, the drum 31 is disengaged but the drum 33 remains 5 engaged. The shovel-skip continues to rise until its upward movement is halted by the engagement of the lower sheave with the carrier. This position of the parts is illustrated in Fig. 4 of the drawing and is called 10 the trammimg position. The shovel skip is automatically locked in the trammimg position by mechanism provided for the purpose. The continued winding of the cable 32 on the drum 33 causes the carrier and 15 shovel-skip to be trammed toward the dumping point. During this trammimg operation the drum 31 is free to revolve and permits the cable 30 to be unwound therefrom. A friction brake is provided on each of the 20 drums 31 and 33 to maintain the cables thereon taut during unwinding. When the shovel-skip has reached the dumping point the drum 33 is disengaged. The dumping device 49 is automatically tripped by the 25 carrier and lifts the handles of the skip to empty the contents in the manner indicated in Fig. 5. As soon as the dumping is completed, the drum 31 is engaged and causes the carrier and shovel-skip to be returned 30 to the loading point. The shovel-skip remains locked in its raised or trammimg position until it has been returned to the loading point where it is automatically released by the adjustable trip 51 mounted on the 35 track, and lowered to the loading position indicated in Fig. 3. During the loading operation the carrier and skip are advanced by the cable 30 at a uniform speed so that these parts are always maintained in substantially 40 vertical alignment. This is a particularly advantageous feature.

Referring to Figs. 7 to 9 inclusive, the power unit 29 comprises upper and lower frames 52 and 53 respectively which are 45 connected by corner irons 54. Trolleys 55 and 56 are secured upon the end pieces of the upper frame 52 midway between the side members of this frame. The trolleys 55 and 56 are provided with rollers 57 and 58 respectively which operate upon the horizontal base flanges of the track 26. Four rollers are provided in each trolley, one pair operating on each side of the central web of the track. These trolleys form a support for the power unit and enable it to travel upon the track. Skids 59 are preferably secured upon the underside of the lower frame 53 to aid in moving the power unit up or down a raise. The electric motor 48 is mounted on the lower frame and a driving shaft 60 is supported in bearings 61 in alignment with the main shaft 62 of the motor. Clutch members 63 and 64 are respectively secured on the opposing 60 ends of the shafts 60 and 62. The shaft

60 is longitudinally slidable to permit the clutch member 63 to be thrown into engagement with the member 64 by the operating lever 65. A gear 66 is secured upon the shaft 62 and is permanently in mesh with a gear 67 on the change speed shaft 68 mounted in brackets 69 on the unit frame. A gear 70 is likewise secured upon the shaft 68 and is adapted to mesh with a gear 71 on the shaft 60. The shaft 60 may be driven either directly by the shaft 62 by the engagement of the clutch members 63 and 64 or indirectly through the gears 66, 67, the shaft 68, and the gears 70 and 71. This latter connection is accomplished by shifting the shaft 60 by means of the lever 65 to disengage the clutch members and bring the gear 71 into engagement with the gear 70 on the change speed shaft. A driving sprocket 72 is splined upon the shaft 60 between the bearings 61. A chain 73 operatively connects the sprocket 72 with a sprocket 74 upon the shaft 75 of the drum 31. The sprocket 74 is normally free to revolve upon this shaft but is adapted to be secured thereto by means of a friction clutch 76 operated by the lever 77. A second sprocket 78 is freely mounted upon the shaft 75 and secured to the sprocket 76. A chain 79 operatively connects the sprocket 78 with a sprocket 80 upon the shaft 81 carrying the drum 33. The sprocket 80 is normally free to rotate upon the shaft 81 but is adapted to be operatively connected thereto by means of a clutch 82 controlled by a lever 83. The bearings 84 and 85 respectively supporting the shafts 75 and 81 are preferably provided with hinged upper sections to permit the drums and drum shafts to be removed from the power unit to lighten the weight of this unit when it is being transferred from one level to another. While the complete power unit is comparatively light in weight and easily movable, it is exceedingly light and easily handled when the drums and drum shafts are removed therefrom. Thrust bearings 84' and 85' are preferably provided upon the shafts 75 and 81 respectively. 100

The motor 48 is operated by a controller 86 mounted on any convenient portion of the unit frame and a resistor 87 permits the regulation of the speed of the motor during the various steps of the mining operation. The direct drive of the shaft 60 by the shaft 62 of the motor provides a rapid rotation of the drums and the indirect drive through the change speed shaft 68 provides a slower rotation. The high speed is desirable during the trammimg operation, whereas the lower speed is usually preferable during the loading and hoisting operations. A brake band 88 is preferably provided on the drum 31 and this brake band is operated by a screw 88' controlled by 105 110 115 120 125 130

a rod 89 connecting to the clutch operating handle 77 in the manner indicated in Figs. 9 and 24. When the clutch 76 is thrown out of engagement this band is simultaneously moved into engagement with the drum and maintains the cable taut. A similar brake band 90 on the drum 33 is operated by the clutch lever 83. The movement of the lever to engage the clutch releases the brake band.

The power unit is moved from one drift to another by means of turntables 47 located at track intersections. The turntable 47, shown in detail in Figs. 10 and 11, comprises a frame composed of channel irons 95 and 96 connected by cross-braces 97 and 98 stiffened by corner plates 99. These channel irons rest on the roof beams 22 of the mine and form the support for the turntable.

20 Semi-circular track segments 100 and 101 are secured by bolts or other suitable means to the underface of the supporting frame of the turntable. Track sections 102 are suspended from the circular track by trolleys 103. The particular turntable illustrated in the drawings is intended for a two-unit system such as is shown in Figs. 1 and 2, and therefore two parallel track sections 102 are provided to form the connecting links between their respective tracks 26. These track sections 102 are adapted to be swung by the turntable to register with the terminals of other tracks of the same line intersecting at the turntable. The trolleys 30 consist of oppositely disposed side plates 104, each having a pair of rollers mounted on stud shafts 104' on their inner faces to operate upon the opposite base flanges of the circular track. These plates are secured to a block 106 by means of a bolt 107 and this block is connected to the upper portion of the track section 102 by straps 108. In order to facilitate handling of the turntable, the supporting frame may be formed in two sections connected by the clamps 109.

45 The carrier 28 is shown in detail in Figs. 15 and 16 and comprises a pair of oppositely disposed plates 110, each of which is provided upon its inner face with a pair of rollers 111 substantially in horizontal alignment and revolvably mounted on stud bolts 112 passing through the plate. A small shaft or pin 113 passes through the plates 110 and forms the axle for the sheave 44. 50 The hoisting cable 32 operates in this sheave and supports the lower sheave 45. The upper sheave 44 in the present embodiment consists of a sprocket 116 having peripherally toothed disks 117 secured on opposite sides thereof. A pawl 118 is mounted in the plates 110 upon a shaft 119 provided at its outer extremities with laterally projecting arms 120. A bar 121 is pivotally mounted on the outer face of each of the plates 110. 55 The lower end of each of these bars 121 is

connected by a wire or chain 122 with the corresponding arm 120. The wire or chain 122 preferably passes over a pulley 123 so that when the bar 121 is rocked in either direction on its pivot it will cause the arm 120 to be lifted and to move the pawl 118 out of engagement with the teeth on the periphery of the disks 117. The trip block 51 on the track 26 is adapted to rock the bar 121 when this bar is moved into contact therewith by the travel of the carrier on the track. This trip block is secured upon the track at the loading point and advanced thereon as the work progresses. The hoisting cable 32 is provided with a short section of chain 125 at the proper point. This chain is composed of a few links of sufficient size to admit the teeth 126 on the sprocket 116 in the manner indicated in Fig. 15 of the drawings. The sprocket sheave 85 116 is preferably provided with a central peripheral groove 127 to receive the rope portion of the cable 32. The lower sheave 45 is of the type generally used in hoisting apparatus and is provided with a depending snap hook 128 or clasp to engage the ring 129 on the bail or support of the shovel skip 42. When it is desired to move mine timbers the shovel-skip may be detached from this hook 128 and tongs 130, shown in Fig. 14, substituted therefor.

50 A drum 38 is supported by oppositely disposed arms 132 secured to or formed on the plates 110 of the carrier 28. This drum is adapted to be wound by a manually operated handle 133 and is prevented from normally unwinding by a ratchet 134 and pawl 135. The branch 36 of the cable 30 is adapted to be attached to and wound upon this drum so that the length of this branch 105 from the division to the drum may be adjusted for the particular length of travel of the carrier between the loading point and the dumping point. This prevents the divided portion of the cable 30 from being 110 wound on the power drum. The capacity of this drum should be equal to the maximum distance of the loading point from the dumping point and all the cable will thus be unwound from this drum when the loading is at the maximum distance from the power unit. The operation in a drift will start with practically all of the cable portion 36 unwound on the drum 38 and as the drift is extended the cable will be gradually 115 wound by the operator. The oppositely disposed plates 110 of the carrier preferably project below the lower edge of the disks 117 and these lower ends are connected by a small channel 136. Similarly the upper extremities of the side plates 137 of the lower sheave 45 extend above the periphery of the wheel 139 and are connected by a channel 138 disposed opposite to the channel 136 connecting the lower extremities of 120 125 130

the plates 110. When the sheave 45 is being hoisted to trammimg position by the cable 32 these channels come in contact and limit the upward movement of the lower sheave. The continued winding of the cable 32 then causes the carrier to be trammed toward the power unit. At this time the chain 125 is in engagement with the teeth of the sprocket 126 and the sprocket is locked by the pawl 118 so that the lower sheave is retained in its raised position while the shovel-skip is being trammed to the dumping point, dumped and returned to the loading point.

When only one power unit is used in a drift, we have found it advantageous to attach jacks 145 to the upper frame of the power unit in the manner illustrated in Figs. 19 and 23. The upper jack member 146 engages the roof supporting timbers of the mine and prevents rocking of the unit. When two or more units are used in the same drift as indicated in Fig. 2, the frames of the units may be tied together by angles 147 and 148 (Figs. 25 and 26) or any other suitable means. No jacks are needed when units are secured together.

Any suitable form of automatic dumping device for the shovel-skip might be used but we have found a particularly advantageous type for a two unit system to be that indicated in Figs. 20 to 22 inclusive in which a pair of pneumatic cylinders 150 is secured upon a frame 149 composed of cross plates 151 having their corresponding opposite ends connected by a pair of angle irons 152 spaced to receive a cylinder. This frame 149 is adapted to rest upon the upper face of the tracks 26 or the track sections 102 and be clamped thereto at the desired dumping point. An air supply pipe 153 on the frame 149 is connected by a hose with a source of compressed air supply. Each of the cylinders is provided with a piston 154 to which is connected the usual piston rod 155. A sheave 156 is mounted in the outer extremity of each of these piston rods. The trip for engaging the handles on the shovel-skip consists of a bar 157 suspended at its opposite ends by cords or chains 158. Each of these cords passes upwardly over its respective idler 159 supported between the angle irons 152 and thence about the sheave 156 with its end secured to the pin 160 extending between the angle irons 152. Two pipes 162 and 162' connect the main air pipe 153 with the pipe 163 communicating with the cylinders 150. Three-way valves 161 and 161' are provided in the pipes 162 and 162' and these valves are respectively controlled by depending arms 164 and 164' adjacent to their corresponding track section. These arms 164 and 164' are controlled by springs 165 and 165' respectively to normally maintain the valves in closed position. When the

carrier on either track reaches the dumping point, it contacts with the lower extremity of the valve arm for that track and causes the corresponding valve to be opened, admitting air to both cylinders 150 in front of the pistons 154 and drawing the piston rods into the cylinders. This movement of the piston rods 155 draws the sheaves 156 away from the pins 160, and the cords 158 cause the bar 157 to be uniformly and quickly raised beneath the handles 50 on the shovel-skip 42. The load is dumped in the manner indicated in Fig. 5 of the drawings. The movement of the carrier toward the power unit is stopped at this time by releasing the clutch operating the drum 33. The drum 31 is next engaged and the carrier returned to the loading point. The return movement of the carrier releases the valve arm and the valve is closed by its spring. The closing of the valve permits the air in the cylinders to exhaust. The weight of the bar 157 then draws the sheaves 156 to their outer position and the trip is ready to engage the next shovel-skip to reach the dumping point. The use of two sheaves for each cord 158 compounds the power of the cylinders and insures quick dumping action of the bar 157.

Fig. 27 shows a typical iron ore sub-level with the usual drifts, breasts and raises. This figure illustrates the adaptability of the apparatus in passing around turns in the drifts.

Fig. 28 shows a modified form of the invention in which the power unit 173 is located on a truck at the bottom of the raise and the cables are conducted to the sub-level drift by means of idlers 174. The construction of the mechanism in this case is the same as that described for the previous embodiment except that no turntables are necessary and the dumping trip is located above the mouth of the raise. The shovel-skip is illustrated in the loading, the dumping and the trammimg positions.

Fig. 29 illustrates the adaptability of the apparatus in eliminating manual labor. The shovel-skip has been removed from the carrier and timber handling tongs, shown in Fig. 14, have been connected to the carrier. The timbers 175 needed for further extension of the drift are being hoisted from the main level 176 and transported directly to the breast. This greatly facilitates the extension of the mining operation and produces a very material saving in labor.

Fig. 30 illustrates the use of the apparatus in handling ore in the main level. The dumping trip is moved along on the overhead track from car to car as each car is successively filled. The entire train is loaded without shifting a single car. No loading platforms or stands for the cars are needed.

Fig. 31 illustrates the use of the present invention in conducting mining in a narrow or badly crushed drift. This drift is so narrow that it would be impossible for an ordinary mining car to enter. The single overhead track which carries the shovel skip may be easily suspended from small track supports and the mining operations can be conducted as readily as in a full width drift.

All bending of track in the mine is eliminated as the overhead track sections are brought to the mine properly bent. The sections are selected to conform to the general direction of the drift and the apparatus will work equally well in either a straight or crooked drift. The ore is conducted in the shovel-skip entirely clear of the floor of the drift so that the ore is not scattered along the drift. This is a very great improvement over the scraper type of apparatus in which the loaded scraper is dragged on the floor and the constant bumping partially empties the scraper before it reaches the dumping point. The overhead system of trackage may be quickly installed without the necessity of laying tracks with ties and the moving of cars by manual labor in these drifts is eliminated.

The power unit is simple in construction and light in weight so that it may be easily moved from place to place on the overhead track system. The unit may be made still lighter in weight by removing the drums from the unit frame. This is easily accomplished on account of the hinged bearings. In order to facilitate the movement of the power unit about the mine the frame has been equipped with skids which will enable the unit to be easily drawn up or down the raise from one level to another. The power unit is particularly adapted to use electrical power which is both economical and convenient. Practically all of the larger mines are equipped with electric wiring and the power unit may be plugged in at any desired point. Where it is inconvenient or inadvisable to use electric power, the unit may be provided with a compressed air motor or any other suitable power mechanism. The entire construction including the power unit is substantially noiseless in operation so that the usual noise and confusion in the mine are eliminated. The entire apparatus is easily controlled and operated by two men, one acting as watcher and the other operating the power unit. The construction and operation of the entire device is so simple that highly skilled labor is not necessary.

The loading of the shovel-skip by a forward and upward movement is particularly advantageous for it permits the thorough cleaning of the breast which is not possible with the scraper type of apparatus. The

simultaneous hoisting and advancing of the shovel-skip prevents the same from becoming blocked in the pile of loose material on account of contact with large chunks of ore. The simultaneous forward movement of the carrier and shovel-skip is particularly advantageous. No loss of rails occurs as the overhead track may be quickly and easily removed and conducted to a different part of the mine. The ore is removed in such a short time that a very material saving is produced in retimbering costs. Careful grading of the track is unnecessary. The apparatus will load into a car of any dimensions in main level drifting, whereas most loaders require a car of definite height.

We are aware that many changes may be made in the construction and arrangement of parts without departing from the scope of our invention and we reserve the right to make all such as fairly fall within the scope of the following claims.

We claim as our invention:

1. A mining apparatus comprising a system of overhead trackage suspended from the roof supporting timbers of the mine, a power unit supported by said trackage and adapted to travel thereon, a carrier adapted to travel on said trackage independently of said unit, a shovel-skip suspended from said carrier, and means actuated by said power unit for loading said shovel-skip at the breast and transporting said shovel-skip on said carrier between the breast and the dumping point.

2. In apparatus for underground mining, a system of overhead trackage suspended from horizontal supporting timbers in the mine, a carrier adapted to travel on said trackage, a hoisting and traversing cable, a shovel-skip suspended from said carrier by said cable, a loading and traversing cable having a divided end connected to said carrier and said shovel-skip to cause said carrier and said shovel-skip to advance in substantially vertical alignment during the loading operation, and operating drums for each of said cables, said drums being mounted independently of said carrier.

3. In apparatus for underground mining, a system of overhead track suspended from horizontal supporting timbers in the mine, a carrier traveling upon said track, a shovel-skip associated with the carrier, a power unit supported by said track and adapted to travel thereon independently of said carrier, and operating cables connecting said unit, said carrier and said shovel-skip.

4. In apparatus for underground mining, a system of overhead intersecting trackage suspended by flexible connections from the roof supporting beams of the mine, turntables located at track intersections in said system, a carrier traveling on said trackage, a shovel-skip suspended from said carrier,

a power unit traveling on said trackage independently of said carrier, and operating cables connecting said unit with said carrier and said shovel-skip.

5 5. In apparatus for underground mining, a system of overhead intersecting trackage suspended from the roof supporting beams of the mine, an electrical power unit suspended from said trackage and traveling thereon, a carrier traveling on said trackage independently of said unit, turntables located at track intersections for shifting said unit and said carrier from one track to another in said system, a shovel-skip supported by said carrier, and means actuated by said unit for loading and trammimg said shovel-skip.

15

6. In apparatus for underground mining, a system of overhead trackage suspended from the roof supporting beams of the mine, a power unit supported by said trackage and adapted to travel thereon, a carrier traveling on said trackage independently of said unit, a shovel-skip suspended from said carrier, and means actuated by said unit for loading said shovel-skip at the loading point, hoisting the loaded shovel-skip into tramming position, tramming said shovel-skip to the dumping point, and returning the empty shovel-skip to the loading point.

35 7. In an apparatus for underground mining, a system of overhead trackage suspended from the roof supporting beams of the mine, a power unit supported by said trackage and adapted to travel thereon, a carrier traveling on said trackage independently of said unit, a shovel-skip suspended from said carrier, means actuated by said unit for loading said shovel-skip at the loading point, hoisting the loaded shovel-skip into tramping position, tramping said shovel-skip to the dumping point and returning the empty shovel-skip to the loading point, means for automatically dumping said shovel-skip at the dumping point, and means for automatically lowering said shovel-skip to loading position at the loading point.

50 8. In apparatus for underground mining, a system of overhead trackage suspended from horizontal supporting beams in the mine, a power unit supported by said trackage and adapted to travel thereon, a carrier traveling on said trackage independently of said unit, a shovel-skip suspended from said carrier, means actuated by said unit for loading said shovel-skip at the loading point, hoisting the loaded shovel-skip into tramping position, tramping said shovel-skip to the dumping point, and returning the empty shovel-skip to the loading point, means for maintaining said shovel-skip in its raised or tramping position during the tramping operation, and

means for automatically releasing said shovel-skip at the loading point.

9. In apparatus for underground mining, a system of overhead trackage suspended from the roof supporting beams of the mine, a power unit supported by said trackage and adapted to travel thereon, a carrier traveling on said trackage independently of said unit, a shovel-skip suspended from said carrier, means actuated by said unit for loading said shovel-skip at the loading point, hoisting the loaded shovel-skip into tramping position, tramping said shovel-skip to the dumping point and returning the empty shovel-skip to the loading point, means controlled by the movement of said carrier for automatically dumping said shovel-skip at the dumping point, and means controlled by the movement of said carrier for lowering said shovel-skip to loading position at the loading point.

10. A mining apparatus comprising a system of overhead trackage suspended from horizontal supporting beams in the drift, a carrier adapted to travel on said trackage, a shovel-skip suspended from said carrier, a power drum, and an operating cable having a divided outer end connected to said carrier and said shovel-skip to simultaneously advance said carrier and said shovel-skip during the loading operation. 90 95

11. In apparatus for underground mining, a system of overhead trackage suspended from the roof supporting beams 100 of the mine, a carrier traveling on said trackage, a sprocket sheave mounted on said carrier, a lower sheave suspended from said carrier by a hoisting cable passing over said sprocket sheave and provided with a short chain section for engagement with the teeth on said sprocket sheave when said lower sheave is in its raised position, a 105 ratchet normally permitting rotation of said sprocket sheave in one direction only, and a trip on said trackage for releasing said sprocket from said ratchet and permitting the escape of said chain section therefrom. 110

12. In apparatus for underground mining, a system of overhead trackage suspended from horizontal supporting beams in the mine, a carrier adapted to travel on said trackage, a power drum, an operating cable connecting said drum and said carrier, and a cable adjusting drum mounted on said carrier. 115
120

13. In apparatus for underground mining, a system of overhead trackage suspended from the roof supporting beams of the mine, a carrier adapted to travel on said trackage, a power drum, an operating cable connecting said drum and said carrier, and a ratchet controlled, cable adjusting drum mounted on said carrier. 125 130

14. In apparatus for underground mining, a suspended system of overhead trackage, a carrier adapted to travel on said trackage, a shovel-skip suspended from said carrier, an operating cable formed with a divided outer end having one branch connected to said carrier and the other branch
- connected to said shovel-skip, and a drum mounted on said carrier for adjusting the length of the cable branch connected to 10 said carrier.
